UNITED STATES PATENT OFFICE.

JESSE P. MOLLENKOF, OF ERDENHEIM, PENNSYLVANIA, ASSIGNOR TO JOHN H. McCLATCHY, OF PHILADELPHIA, PENNSYLVANIA.

DESIGN FOR A COLUMN.

Application filed October 2, 1923. Serial No. 7,378. Term of patent 14 years.

To all whom it may concern:

Be it known that I, JESSE P. MOLLENKOF, a citizen of the United States, residing at Erdenheim, in the county of Montgomery and State of Pennsylvania, have invented a new, original, and ornamental Design for a Column, of which the following is a specification, reference being had to the accom-

panying drawing, forming a part hereof, in which the single figure is a perspective view of a column showing my new design.

I claim:—

The ornamental design for a column, substantially as shown.

JESSE P. MOLLENKOF.
